UNITED STATES PATENT OFFICE.

OTIS W. EVERETT, OF WORCESTER, MASSACHUSETTS, ASSIGNOR TO THE SAMUEL WINSLOW SKATE MFG. COMPANY, A CORPORATION OF MASSACHUSETTS.

ROLLER-SKATE.

No. 823,940.

Specification of Letters Patent.

Patented June 19, 1906.

Application filed January 28, 1906. Serial No. 297,937.

To all whom it may concern:

Be it known that I, OTIS W. EVERETT, a citizen of the United States, residing at Worcester, in the county of Worcester and State of Massachusetts, have invented certain new and useful Improvements in Roller-Skates, of which the following is a specification.

My invention relates to roller-skates and to the class of roller-skates which have rocking or tilting trucks for the rollers.

The object of my invention is to improve upon the construction of roller-skates of the class referred to, and more particularly to strengthen the foot-plate and to improve upon the construction of the roller-trucks and to provide means for regulating or adjusting the rocking or tilting movement of the roller-trucks.

My invention consists in certain novel features of construction of my improvements, as will be hereinafter fully described.

Referring to the drawings, Figure 1 is a side view of a roller-skate embodying my improvements. One roller at the front of the skate is left off in this figure. Fig. 2 is a cross-section on line 22, Fig. 1, looking in the direction of arrow *a*, same figure. Figs. 3, 4, 5, 6, 7, and 8 show the several parts of the roller-truck detached from the skate and from each other; and Fig. 9 is a plan view of the hanger shown in Fig. 3 looking in the direction of arrow *b*, same figure.

In the accompanying drawings, 1 is the foot-plate of the skate, preferably made of sheet metal and having the toe-clamps 2 at the front end thereof, which are adjusted by a key, (not shown,) turning a right and left hand threaded screw 3 (see Fig. 2) in the usual way. At the rear end of the foot-plate 1 are in this instance upwardly-extending projections 1', only one of which is shown, for engaging the heel and having secured thereto the end of a strap 4, which passes around the foot at the ankle portion in the usual way. The foot-plate 1 has in this instance its side edges intermediate the ends of the plate bent or pressed downwardly, as shown at 1'', to form downwardly-curved flanges, which extend at substantially right angles to the foot-plate 1, as shown in Fig. 2. The flanges 1'' act to strengthen the foot-plate 1.

Extending through the central portion of the foot-plate 1, on the under side thereof, I

preferably have a supplemental plate or bar 5, which is of truss shape and is riveted at its ends to the foot-plate 1 and is secured at its central portion to the under side of the foot-plate 1 by a stud 6. (See Fig. 1.) The supplemental plate or bar 5 acts to strengthen and make more rigid the foot-plate 1 and may be flat or of other shape in cross-section. The two roller-trucks are of the same construction, and a description of one will answer for both.

The truck hanger or bracket 7 is preferably made of sheet metal of substantially the shape shown, having two upright portions 7' with side extensions 7'', which are riveted to the foot-plate 1, (see Fig. 2,) and the forwardly-extending portion with the two side extensions 7''' thereon, which are riveted to the foot-plate 1. A plate 8, having downwardly-extending side flanges 8', and a downwardly-extending end 8'', having an opening therethrough, extends upon the under side of the hanger or bracket 7 and is riveted thereto.

A block of rubber or other yielding material 9, forming a cushion, extends between the side flanges 8' on the plate 8 and is held in position and adjustably compressed by a plate 10, termed the "roller-carrier," and in this instance made in two parts 10' and 10'' riveted together, which extends upon the under side of the yielding block 9 and has one end bent upwardly and a stud 11 secured therein, which is adapted to extend loosely through the opening in the downwardly-extending end 8'' on the plate 8 and to act as a pivot-stud. The other end of the plate 10 has a hole therethrough to loosely receive an adjusting bolt or screw 12. The screw 12 has a nut 13 on its threaded portion, and its threaded end is adapted to be screwed into a threaded hole in the end of the plate 8 and in the hanger or bracket 7 to secure the end of the plate 10 to the end of the plate 8 and the hanger 7 and to secure the yielding block 9 between the same.

Extending down from the plate or roller carrier 10, and in this instance forming a part thereof, is a bearing 10^a for the axle 14 of the rollers 15. The rollers 15 are preferably of metal, having metal rims, and are provided with ball-bearings and are mounted to turn on the axle 14, which in this instance is stationary.

Any suitable and well-known construction

of rollers may be employed; but I prefer to construct the rollers 15 in the manner shown and described in my pending application for Letters Patent, Serial No. 263,712.

5 By means of the adjusting screw or bolt 12 the end of the plate or roller carrier 10 may be moved toward or away from the plate 8 to compress or release the yielding block or cushion 9 and regulate the action thereof, as 10 desired, to regulate and adjust the rocking or tilting movement of the plate or roller carrier 10, and to cause said roller-carrier to rock or tilt with greater or less freedom, as will be well understood.

15 It will be understood that the details of construction of my improvements may be varied, if desired.

Having thus described my invention, what I claim as new, and desire to secure by Letters Patent, is—

20 1. In a roller-skate, a roller-truck adapted to be secured to the under side of the foot-plate, comprising a metal hanger or bracket having attaching ends, a plate secured to the under side of said hanger or bracket, and having an opening therein for a pivot-stud, and for an adjusting-screw, and a second plate or roller carrier having a stud thereon adapted to enter the opening in the first-mentioned

plate, and a hole therein to receive the adjusting-screw, and also having a bearing thereon for the axle of the rollers, a yielding block or cushion extending between said two plates, and a screw or bolt for adjusting the relative position of said plates, to regulate the action 35 of said cushion.

2. In a roller-skate, a roller-truck adapted to be secured to the under side of the foot-plate, comprising a metal hanger or bracket having attaching ends, a plate having down- 40 wardly-extending edges intermediate its ends, secured to the under side of said hanger or bracket, and having an opening therein for a pivot-stud, and for an adjusting-screw, and a second plate having a stud thereon adapted 45 to enter the opening in the first-mentioned plate, and a hole therein to receive the adjusting-screw, and also having a bearing thereon for the axle of the rollers, a yielding block or cushion extending between said two plates, 50 and a screw or bolt for adjusting the relative position of said plates, to regulate the action of said cushion.

OTIS W. EVERETT.
